T. M. FOSS

WRENCH

Filed Oct. 9, 1925

UNITED STATES PATENT OFFICE.

THOMAS MARTIN FOSS, OF MINNEAPOLIS, MINNESOTA, ASSIGNOR OF ONE-HALF TO
BURR M. COLE, OF MINNEAPOLIS, MINNESOTA.

WRENCH.

Application filed October 9, 1925. Serial No. 61,461.

My present invention has for its object to provide an extremely simple and highly efficient quick-acting wrench, and to this end it consists of the novel devices and combinations 5 of devices hereinafter described and defined in the claims.

In the accompanying drawings, which illustrate the invention, like characters indicate like parts throughout the several views.

10 Referring to the drawings:

Fig. 1 is a side elevation of the invention embodied in a pipe wrench;

15 Fig. 2 is a view corresponding to Fig. 1, but showing certain of the parts in section; and

Fig. 3 is a fragmentary view corresponding to Fig. 1 but illustrating the invention embodied in a monkey wrench.

Referring first to the invention as illustrated in Figs. 1 and 2, the numeral 4 indicates the bar-like body of a pipe wrench that is rectangular in cross section. On one end of the body 4 is a fixed jaw 5 and the other end thereof affords a handle 6. Cooperating 20 with the fixed jaw 5 is a movable jaw 7 having a passageway 8 through which the body 4 extends and supports said jaw for sliding adjustment toward and from the fixed jaw 5. The size of the passageway 8 is such as to 25 hold the movable jaw 7 against lateral or turning movements on the body 4 but with freedom for slight rocking movement toward and from the fixed jaw 5.

A multiplicity of longitudinally spaced 30 teeth 9 are formed with the body 4, and meshing with said teeth is a toothed wheel 10 mounted in a recess 11 in the back or one end of the movable jaw 7 and journaled thereto at 12. This toothed wheel 10 also affords a 35 pivot on which the rocking jaw 7 is free for movement in the arc of a circle with the axis of said wheel as the center.

For locking the toothed wheel 10 against rotation in a direction to permit a movement 40 of the movable jaw 7 away from the fixed jaw 5 but permit free movement thereof toward said fixed jaw, I provide a pair of spring-pressed dogs 13. These dogs 13 are located within the recess 11, loosely mounted 45 on a common pivot 14 secured to the movable jaw 7, and arranged to alternately move into and out of interlocking engagement with the toothed wheel 10, forward of its pivot 12.

By reference to Fig. 2 it will be noted that the dogs 13 are circumferentially spaced so 50 that when one of said dogs is interlocked with the toothed wheel 10 the other thereof rests on an adjacent tooth of said wheel, thus giving the movable jaw 7 a relatively fine adjustment.

Formed with the dogs 13 are releasing levers 15 that extend outward of the recess 11, substantially parallel to the body 4, and the arrangement of said levers is such that the one on the dog 13, having interlocking 55 engagement with the toothed wheel 10, extends outward of the other lever so that the same may be readily operated to release the respective dog without operating the other lever 15.

A fixed face plate 16 is attached to the fixed jaw 5 by a single screw 17 and a transversely extended rib and slot connection 18, which securely holds said plate against turning movement on the screw 17. The rib of 60 the connection 18 is rigidly secured to the fixed jaw 5, and the slot thereof is formed in said plate. The movable jaw 7 is provided with a face plate 19 pivoted thereto at 20 for a rocking movement in the plane of the rocking movement of said jaw. This rocking face plate 19 will automatically adjust itself onto a pipe or other object held by the jaws 5 and 7.

From the above description it is evident 65 that the movable jaw 7 may be freely slid toward the fixed jaw 5, and at which time the toothed wheel 10 will be rotated by its engagement with the fixed teeth 9 and move over the dogs 13 with a ratchet-like action. 70 When the movement of the movable jaw 7 is stopped by its engagement with a pipe or other object to which the wrench is to be applied, one of the dogs 13 will be interlocked with the toothed wheel 10 to prevent backward 75 rotation thereof and lock said jaw where set. To release the wrench from the object to which it is applied it is only necessary to depress the outermost lever 15 to raise the respective dog 13 and thereby release the toothed wheel 10. At the time the outermost lever 15 is depressed, the other of 80 said levers will be held by the operator to prevent the respective dog 13 from moving into interlocking engagement with the toothed wheel 10. With the lock dogs 13

held out of interlocking engagement with the toothed wheel 10, the movable jaw 7 may be freely slid on the body 4 away from the fixed jaw 5.

Referring now to the invention as illustrated in Fig. 3, the numeral 21 indicates the bar-like body of a monkey wrench, on one end of which is a fixed jaw 22 and on the other end of which is applied a handle 23. Co-operating with the fixed jaw 22 is a movable jaw 24 slidably mounted on the body 21. Formed with the body 21 is a multiplicity of longitudinally spaced teeth 25 with which mesh a toothed wheel 26 loosely journaled on a pivot pin 27 carried by the movable jaw 24 and located in a recess 28 formed in the back thereof. Circumferentially spaced lock dogs 29, located in the recess 28 and mounted on a common pivot pin 30, are arranged to alternately move into and out of interlocking engagement with the toothed wheel 26 and thereby lock the same against rotation by a movement of the movable jaw 24 away from the fixed jaw 22 but to move over the toothed wheel 26 with a ratchet-like action during the movement of the jaw 24 toward the fixed jaw 22. Releasing levers 31 are formed with the lock dogs 29.

The means for holding the movable jaw 24 are identical with the means for holding the movable jaw 7 and the action thereof is the same.

What I claim is:

1. A wrench comprising a body having a fixed jaw and a co-operating movable jaw, the latter of which is slidably mounted on the body, there being teeth on the body, a toothed wheel journaled on the movable jaw at the end thereof and meshing with said teeth, and a spring-pressed dog mounted on the movable jaw for co-operation with the toothed wheel, said movable jaw being free for rocking movement on the toothed wheel

in the arc of a circle with the axis of said wheel as the center while said dog is interlocked with the toothed wheel.

2. A wrench comprising a body having a fixed jaw and a co-operating movable jaw, the latter of which is slidably mounted on said body, there being teeth on the body, a toothed wheel journaled on the movable jaw and meshing with said teeth, and a pair of circumferentially spaced spring dogs mounted on the movable jaw and arranged to alternately move into and out of interlocking engagement with the toothed wheel with a ratchet-like action by a movement of the movable jaw toward the fixed jaw, said dog having levers for releasing the same and which levers are so arranged that the one on the dog having interlocking engagement with the toothed wheel extends outward of the other of said levers.

3. A wrench comprising a body having a fixed jaw and a co-operating movable jaw, the latter of which is slidably mounted on the body, there being teeth on the body, said movable jaw having in its back a recess, a toothed wheel mounted in the recess, journaled on said jaw and meshing with said teeth, and a pair of circumferentially spaced spring-pressed dogs mounted on the movable jaw in its recess and on a common axis and arranged to alternately move into and out of interlocking engagement with the toothed wheel, said dogs having levers for releasing the same, extending outward of the recess and arranged so that the one on the dog having interlocking engagement with the toothed wheel extends outward of the other of said levers, said movable jaw being free for rocking movement on the toothed wheel in the arc of a circle with the axis of said wheel as the center.

In testimony whereof I affix my signature.
THOMAS MARTIN FOSS.
